(No Model.)

H. H. GARLAND.
FISH HOOK HOLDER.

No. 595,998.

Patented Dec. 21, 1897.

UNITED STATES PATENT OFFICE.

HORATIO H. GARLAND, OF BROOKLYN, NEW YORK.

FISH-HOOK HOLDER.

SPECIFICATION forming part of Letters Patent No. 595,998, dated December 21, 1897.

Application filed June 10, 1897. Serial No. 640,153. (No model.)

To all whom it may concern:

Be it known that I, HORATIO H. GARLAND, of Brooklyn, in the county of Kings and State of New York, have invented a new and Improved Fish-Hook Holder, of which the following is a full, clear, and exact description.

The object of the invention is to provide a new and improved fish-hook holder which is simple and durable in construction and arranged to permit of conveniently and securely storing a large number of hooks and their snells in a comparatively small space and with the points of the hooks well protected and the snells perfectly straight, and also arranged to permit a fisherman to readily remove or replace any desired hook or snell at any time without disturbing or disarranging the others.

The invention consists in certain features of construction that will be fully described hereinafter, and defined in the claims.

Reference is to be had to the accompanying drawings, forming a part of this specification, in which similar characters of reference indicate corresponding parts in all the figures.

Figure 1 is a face view of the improvement. Fig. 2 is an edge view of the same, and Fig. 3 is a transverse section of the same on the line 3 3 of Fig. 1.

The improved fish-hook holder is provided with a holder A proper, formed at its ends with forks B B', having their members provided at their outer ends with lugs or projections C C' and C² C³, respectively, as plainly indicated in the drawings. The projections at the ends of the fork members are placed a suitable distance apart, so that the bent portion of the shank of the hook D can be readily passed between two adjacent projections, so that the hook end passes between the members of the forks, as plainly indicated in the drawings.

The snell E for each hook D is engaged at its loop E' with an endless elastic band F, adapted to be doubled up and hooked upon a projection at the opposite end of the holder on which the hook D is engaged. For instance, a hook D engaging the front member of the fork B has the elastic band F for its snell engaging a projection C² on the front member of the other fork B', as shown in the drawings.

In a like manner a hook D may engage the rear member of the fork B', and its snell is then connected by an elastic band F with a

projection C' of the rear member of the fork B, as illustrated in the drawings. Thus hooks may be placed on each of the forked members and the snells extended over the front and rear faces of the holder and connected by elastic bands with projections at the ends of the holder.

As shown in the drawings, the holder is arranged for two dozen hooks and their snells, and it is evident that, owing to the elastic bands, any desired hook can be readily lifted out of the forked member and disengaged from the holder upon removing the elastic band from the snell. While such a hook is in use by a fisherman the elastic band F is hung over a lug G, having inwardly-beveled sides and formed at the side of the holder, as plainly indicated in the drawings.

The holder A may be made of sheet metal or other suitable material, or of wood, by providing front and back plates A' A², connected with each other at their opposite faces near the top and bottom ends by blocks A³ A⁴, so as to form the forks at the ends of the holder, the members of the forks being the ends of the plates.

It will be seen that by the arrangement described the hooks can be conveniently stored, so as to completely protect their points and keep the snells straight to prevent entangling of the snells and hooks and at the same time permit of convenient removal of any one of the hooks for immediate use whenever desired.

Having thus fully described my invention, I claim as new and desire to secure by Letters Patent—

1. A fish-hook holder, provided with a holder proper, adapted to carry on one end a hook, the shank of which extends between spaced projections formed at said end, and an elastic band adapted to engage the loop of a snell, and adapted to be hooked or looped upon a projection at the other end of the holder, substantially as shown and described.

2. A fish-hook holder, provided with a holder proper, forked at each end for the reception of the shanks of the hooks, with the hook-points between the members of the forks, and with the bent shank portions resting with their outer edges on the forked members, and projections on the ends of the forked mem-

bers, for separating adjacent hooks and receiving elastic bands for the snells of the hooks, substantially as shown and described.

3. A holder for fish-hooks, having each end 5 forked and the members of each fork having lugs or projections extending outward from the said members, and capable of receiving

the fish-hooks between them, and of holding means for retaining the fish-hooks.

HORATIO H. GARLAND.
